UNITED STATES PATENT OFFICE.

JOHN BERNINI, OF ALLENTOWN, PENNSYLVANIA.

WARP LET-OFF MECHANISM FOR LOOMS.

Application filed October 18, 1927. Serial No. 226,902.

The present invention relates to improvements in warp let off mechanism for looms such as is disclosed in Letters Patent No. 1,622,757 dated March 29, 1927.

5 An important object of the invention resides in the provision of a standard beam head particularly well adapted for mounting the let off mechanism and further in the provision of improved means of superior accuracy and capable of simpler adjustment and designed for the introduction of springs pulling from an angle instead of the usual weight.

With the above and numerous other objects in view as will appear as the description 15 proceeds, the invention resides in certain novel features of construction, and in the combination and arrangement of parts as will be hereinafter more fully described and claimed.

20 In the drawings:

Figure 1 is an elevation of the mechanism embodying the features of my invention,

Figure 2 is another elevation thereof taken at right angles to that shown in Figure 1, 25 showing portions of the sections and the worm gear being omitted for clarity.

Figure 3 is a fragmentary side elevation showing portions of a machine with my improved let off mechanism mounted thereon,

30 Figure 4 is an elevation of one of the caps, Figure 5 is another elevation thereof,

Figure 6 is a detail view of the springs,

Figure 7 is a top plan view showing a portion 35 of the mechanism, and

Figure 8 is an elevation similar to Figure 1 showing a modification.

Referring to the drawing in detail it will be seen that the numeral 7 denotes a gear formed with an annular member 8 projecting

40 into a ring 5 and on which this ring 5 is rotatable. A pinion 9 and a worm gear 10 are joined together and are rotatable on a stud 14 projecting from the ring 5. The pinion 9 meshes with the gear 7 and the worm gear

45 10 meshes with a worm 11. This worm 11 is journaled between ears 12 and 13 projecting from the ring 5. A ratchet 15 is fixed on a shaft forming part of the worm 11 and designated specifically by the numeral 17. A

50 lever 16 is rotatable on the shaft 17. A spring pressed pawl 30 is mounted on the lever 16 for engaging the ratchet wheel 15. A spring 31 is fixed at one end to the lever 16, coiled about the lever hub and anchored

55 to the ears 12 for normally holding the lever and returning it to a predetermined posi-

tion. A small lever 19 on the pawl 30 is provided for releasing this spring pressed pawl from engagement with the ratchet 15.

In Figure 3 I have given a fragmentary 60 illustration of the mounting of the mechanism on a loom. A link 33 is anchored in a hole 20 of the ring 5 and fastened to an arm 21. Springs 22 are disposed at an angle to the arm 21 and are anchored to the lower loom 65 brace 23 for imparting tension to the warp beam and for compensating the shedding.

At every pick of the loom, the warp threads will rise and fall with the harness frame forming the open and closed shed. As the 70 shed opens, the warp threads are drawn from a straight line and assume a longer distance. This will cause the warp beam to rock, setting the weights in a vertical oscillation. It is apparent that the weight in 75 motion, due to inertia will impart an irregular tension on the warp threads and will not synchronize with the motion of the shed,

especially when the loom is set in operation. If the customary method of using weights 80 for tensioning is used, the let off mechanism will compensate for the taking up of the warp by the take up motion but will depend on gravity to compensate for the motion of the harness shaft.

The positive harness motion or head of a 85 loom of the gem type can be operated by hand independent of the loom motion and I will use it to illustrate the points attempted to be made in the above paragraph. If the loom is stopped and the head motion is unlocked, we can turn the hand crank opening and close the shed. The opening and closing of the shed will cause the warp beam to rock and the weight to move up and down. When 90 I start to turn the hand crank of the head motion opening the shed the warp threads will have to overcome that property of the weight at rest to remain so and as we keep on turning (opening and closing the shed) 95 the warp beams will rock and weight move up and down the warp threads will have to overcome the property of the weight in motion to continue in the same direction (up or down). This is what I mean by "inertia," 100 weight in motion causing irregular tension on the warp threads if weights are used.

To eliminate gravity and to reduce inertia I use springs 22 and make their use practical for warp tensioning and to compensate the 110 shedding by applying the same in such a manner as to form an angle with the arm 21.

This arrangement will not increase the pull on the arm 21 if the same is drawn up by the let off mechanism from a predetermined point. After the mechanism has been secured to the warp beam cap 24, the ring 5 is anchored to the lever 21 by means of the hook 33. The worm is turned causing the gear 7 to turn until the slack of the warp threads is taken up. This will stop the gear 10 and cause the ring to move up pulling the arm 21 away from the stop 25. The pull of the springs will tension the warp and the ring will be turned up to the desired position when the lever 16 touches the extreme striking 15 point of the lay rod. As the loom is set in motion, the striking rod 26 will move back and forth (moved by the leg or other suitable part of the loom). The warp is taken up by the take up motion. The striking rod 26 20 strikes the lever 16 which turns the worm and causes the rotation of the worm gear thereby as the pinion which in turn causes the ring to travel about the gear. This will allow the gears (and warp) to move ahead 25 while the ring will remain in the same position. The faster the warp is drawn up the longer will be the sweep of the lever 16 and quicker the motion of the worm and pinion and the gear causing the ring to move back 30 faster thus keeping the same position.

If desired gear 7 can be a worm gear and worm 11' made to mesh with it by changing ears 12' and 13' to a suitable position thus eliminating the intermediate gears (pinion 35 and worm gears).

It is obvious that handle 27 is used to turn the worm in adjustment of the ring. The amount of pull of the spring is regulated by turning the handle 28.

It is thought that the construction, operation, utility and advantages of this invention will now be apparent to those skilled in this art without a more detailed description thereof. The present embodiment of the invention has been disclosed in detail merely by way of example since in actual practice it attains the features of advantage enumerated as desirable in the statement of the invention in the above description.

It will be apparent that changes in the details of construction, and in the combination and arrangement of parts may be resorted to without departing from the spirit or scope

of the invention as hereinafter claimed or sacrificing any of its advantages. 55

Having thus described my invention, what I claim as new is:

1. A mechanism of the class described, including, in combination, a gear adapted to be secured to a warp beam, an annular member 60 on the gear, a ring about the annular member, a pinion meshing with the gear, a lever, means pivotally mounting the lever on the ring, means for rotating the pinion by oscillation of the lever, spring means associated 65 with the lever for holding it in a predetermined position, a link engaged with the ring, a lever, means for pivotally mounting the second mentioned lever at one end of the frame of a loom, and spring tension means 70 engaged with the second mentioned lever at an angle thereto.

2. A mechanism of the class described including, in combination, a gear adapted to be secured to a warp beam, an annular member 75 on the gear, a ring about the annular member, a pinion meshing with the gear, a lever, means pivotally mounting the lever on the ring, means for rotating the pinion by oscillation of the lever, spring means associated 80 with the lever for holding it in a predetermined position, a link engaged with the ring, a lever, means for pivotally mounting the second mentioned lever at one end of the frame of a loom, and spring tension means 85 engaged with the second mentioned lever at an angle thereto, said means comprising a pair of springs, means for anchoring the springs to a portion of the loom frame, and adjustable means for anchoring the springs 90 to the other end of the second mentioned lever so that said springs will be disposed at an angle to the lever.

3. A mechanism of the class described including, in combination, a gear adapted to 95 be secured to a warp beam, an annular member on the gear, a ring about the annular member, a pinion meshing with the gear, means for rotating the pinion, a lever, means for pivotally mounting the lever to one end 100 of the frame of the loom, and spring tension means engaged with the lever at an angle thereto.

In testimony whereof I affix my signature.

JOHN BERNINI.
